The ornamental design for a pet waste collecting device, as shown and described.

DESCRIPTION

FIG. 1 is a top perspective view of a pet waste collecting device, showing our new design.

FIG. 2 is a top view thereof;

FIG. 3 is a bottom view thereof;

FIG. 4 is a left side view thereof;

FIG. 5 is a right side view thereof;

FIG. 6 is an enlarged front view thereof;

FIG. 7 is an enlarged rear view thereof; and,

FIG. 8 is another perspective view thereof, but shown in a configuration of use with a broken line disclosure of a plastic disposable bag.

The broken lines showing the plastic disposable bag in FIG. 8 illustrates environmental structure that forms no part of the claimed design.
